UNITED STATES PATENT OFFICE.

JOHN GROSS, OF OTTAWA, ILLINOIS.

EXTENSION-FILE.

SPECIFICATION forming part of Letters Patent No. 292,484, dated January 29, 1884.

Application filed October 11, 1883. (No model.)

To all whom it may concern:

Be it known that I, JOHN GROSS, a citizen of the United States, residing at Ottawa, in the county of La Salle and State of Illinois, 5 have invented certain new and useful Improvements in Extension-Files, of which the following is a specification, to wit:

This invention relates to an improvement in extension-files; and it consists in a file composed of two parts, one of which slides within the other, substantially as will be hereinafter more fully set forth.

In order to enable others skilled in the art to avail themselves of my invention, I will now 15 proceed to describe its construction and operation, referring to the accompanying drawings, in which—

Figure 1 is a perspective view of my device filled with papers, and Fig. 2 is a similar view 20 broken away to show its construction.

a a' represent the covers or sides of my file, to one of which, *a*, is secured, at its inner end, an extension-section of card-board or other moderately stiff but flexible material, *b*. This 25 extension is upon its end formed with a T-head or tongue, *c*, as represented in Fig. 2. The cover *a* forms a pocket in which is secured a piece of material, *d*, having a slot, *d'*, formed longitudinally down its center, with which the 30 tongue *c* engages, and in which it slides, as seen in Fig. 2.

This file thus becomes a protecting-cover for papers, and the extension is drawn out or pushed in at will to expand or reduce the file 35 to suit its contents, and may thus be made to

hold closely a larger or smaller number of papers, while the two covers cannot be entirely separated by reason of the tongue engaging with the slotted intermediate portion, as shown.

This file may be furnished with a rubber band, tape, or similar device, for securing it when closed.

Having thus fully described my invention, what I claim as new, and desire to secure by 45 Letters Patent, is—

1. A file-holder composed of two covers, one of which forms a pocket into which a connecting-extension secured to the other cover may be pushed, or from which it may be partially withdrawn at will, substantially as and for the purpose set forth.

2. A file-holder made in two parts, one of which forms a pocket containing a slotted intermediate piece, and the other has secured to 55 it an extension formed with a T-head or tongue upon its end, substantially as and for the purpose set forth.

3. In a file-holder, the cover *a*, provided with the extension *b*, having the tongue *c*, in 60 combination with the cover *a'*, forming a pocket in which is secured the intermediate part, *d*, formed with slot *d'*, substantially as and for the purpose set forth.

In testimony whereof I affix my signature in 65 presence of two witnesses.

JOHN GROSS.
